(57) **ABSTRACT**

Compounds of the formula

of which, in exemplary compounds, the thienyl group is attached via the 2-position and;

- (a) A is 3α -(6 β , 7 β -epoxy)-tropanyl methobromide and R_1 is 2-thienyl;
- (b) A is 3α -(6, 7dehydro)-tropanyl methobromide and R_1 is 2-thienyl;
- (c) A is 3β -tropanyl methobromide and R_1 is 2-thienyl; and,
- (d) A is 3α -(N-isopropyl)-nortropanyl methobromide and R_1 is cyclopentyl.

There are anticholinergics. Administered by inhalation, they are useful for the treatment of chronic obstructive bronchitis or slight to moderately severe asthma. Administered by the intravenous or oral routes, they are useful for the treatment of vagally induced sinus bradycardia.

**ESTERS OF THIENYL CARBOXYLIC ACIDS
AND AMINO ALCOHOLS AND THEIR
QUATERNIZATION PRODUCTS**

Matter enclosed in heavy brackets [ ] appears in the original patent but forms no part of this reissue specification; matter printed in italics indicates the additions made by reissue.

This is a continuation of application Ser. No. 08/254,324, filed on Jun. 6, 1994, now abandoned which is a continuation of application Ser. No. 08/100,822, filed on Aug. 2, 1993, now abandoned, which is a continuation of application Ser. No. 07/838,724, filed on Mar. 13, 1992, now abandoned.

The invention relates to novel thiencylcarboxylates of amino alcohols and their quaternary products and to the preparation of the novel compounds and their use as active ingredients in medicaments.

The novel compounds correspond to the formula

10

20

25

30

35

40

45

in which

A represents the group

15

20

25

30

35

40

45

wherein

m and n independently of one another denote 1 or 2,

Q represents one of the double-bonding groups

and

Q' represents the group =NR or the group =NRR', wherein

R denotes H or an optionally halogen-substituted or hydroxy-substituted C₁-C₄-alkyl radical, R' denotes a C₁-C₄-alkyl radical and R and R' together may also form a C₄-C₆-alkylene radical, and wherein, in the case of quaternary compounds, one equivalent of an anion (X⁻) opposes the positive charge of the N atom,

R₁ represents a thiienyl, phenyl, furyl, cyclopentyl or cyclohexyl radical, wherein these radicals may also be methyl-substituted, thiienyl and phenyl may also be fluoro-substituted or chloro-substituted,

R₂ represents hydrogen, OH, C₁-C₄-alkoxy or C₁-C₄-alkyl,

R_a represents H, F, Cl or CH₃ and, if =NR denotes a secondary or tertiary amino group, also the acid addition salts.

In the compounds of formula I, R₁ preferably represents thiienyl, R₂ preferably represents OH. The group —OA preferably has the α -configuration and is derived from, for example scopoline, tropine, granatoline or 6,7-dehydrotropine or the corresponding nor-compounds; however, —OA may also have the β -configuration, as in pseudotropine, pseudoscopoline.

Corresponding radicals are, for example

The substituent R is preferably a lower alkyl radical, such as CH₃, C₂H₅, n-C₃H₇, i-C₃H₇, R' is preferably CH₃. R and R' together are, for example —(CH₂)₅—. As halogen substituents for R, F or, as second choice, Cl are suitable.

If R denotes a halogen-substituted or hydroxy-substituted alkyl radical, it is preferably —CH₂—CH₂F or —CH₂—CH₂OH. Accordingly, the group A represents, for example the radicals of scopoline, N-ethylscopoline, N-isopropylscopoline, tropine, N-isopropyltropine, 6,7-dehydrotropine, N- β -fluoroethyltropine, N-isopropyl-6,7-dehydronorpertropine, N-methylgranatoline or the corresponding quaternary compounds, wherein the anion is preferably Br⁻ or CH₃SO₃⁻.

As the acid radical

(IV)

the following are particularly suitable:

4

---

2. Tablets

5	Active ingredient according to the invention	0.05
	Colloidal silicic acid	0.95
	Lactose	65.00
	Potato starch	28.00
	Polyvinylpyrrolidone	3.00
	Na cellulose glycolate	2.00
10	Magnesium stearate	1.00

The constituents are processed in conventional manner to give tablets of 200 mg.

15 The advantageous properties of the novel compounds are shown, for example, in the inhibition of broncholysis in the rabbit (acetylcholine spasms intravenously). After intravenous administration of the novel active ingredients (dosage 3 µg/kg intravenously), the maximum effect occurred after 20 10 to 40 minutes. After 5 hours the inhibiting effect had still not been reduced to half, that is to say the half effect time is more, in some cases considerably more, than 5 hours, as made clear by the residual effects after 5 hours listed below:

25

	Compound	Residual effect in %
	A	76
	B	76
	C	81
	D	61
	E	68
	F	73
	G	69

Compounds of the formula

40

Compound A	R1
	2-thienyl
	3-thienyl
	2-thienyl
	3-thienyl

The quaternary compounds are particularly suitable for therapeutic application, whereas the tertiary compounds are important not only as active ingredients but also as intermediate products.

The compounds of the invention are strong anti-cholinergic agents and have prolonged action. Action lasting at least 24 hours is achieved at inhaled dosages in the µg range. In addition, the toxicity is in the same range as the commercial product Ipratropium bromide, while at the same time the therapeutic effect is stronger.

The novel compounds are suitable, in accordance with their anti-cholinergic nature, for example for the treatment of chronic obstructive bronchitis and (slight to moderately severe) asthma, also for the treatment of vagally induced 35 sinus bradycardia.

Whereas application of the novel active ingredients (in particular the quaternary compounds) by inhalation is mainly recommended for respiratory tract diseases, as a result of which side-effects are largely eliminated, the application for sinus bradycardia is preferably carried out intravenously or orally. It has thus proved to be advantageous that the novel compounds leave the gastro/intestinal motility largely unaffected.

For administration the compounds of the invention are processed using known auxiliaries and/or excipients to give conventional galenic preparations, for example inhalation solutions, suspensions in liquified propellants, preparations containing liposomes or proliposomes, injection solutions, tablets, coated tablets, capsules, inhalation powders for use in conventional inhalation apparatus.

Formulation examples (measures in weight per cent):

---

1. Controlled dosage aerosol

Active ingredient according to the invention	0.005
Sorbitan trioleate	0.1
monofluorotrichloromethane and	to 100
Difluorodichloromethane 2:3	

The suspension is poured into a conventional aerosol container with a dosage valve. 50 µl of suspension are 65 preferably dispensed per actuation. The active ingredient may also be metered in a higher amount if required (for example 0.02 wt. %).

-continued

Notes:

1. The compounds in which R_1 is not 2-thienyl are racemates.
2. The compounds are 3α -compounds in each case.

Processes known per se are used to prepare the novel compounds.

An ester of the formula

wherein R'' represents a C_1 - C_4 -alkyl radical, preferably a methyl or ethyl radical (R_1 , R_2 and R_a have the above meanings), is preferably transesterified using an amino alcohol of the formula

wherein m , n and Q have the above meanings, Q'' represents $=\text{NR}$ or $=\text{NH}$ and the OH group is in the α - or β -position, in the presence of a conventional transesterification catalyst, and the compound obtained is optionally quaternised

- a) if Q'' denotes $=\text{NR}$ ($R \neq H$), using a reactive mono-functionalised derivative $Z-(C_1\text{-}C_4\text{-alkyl})$ of a corresponding alkane (Z =leaving group)
- or is optionally quaternised
- b) if Q'' denotes $=\text{NH}$, using a terminally disubstituted alkane $Z-(C_4\text{-}C_6\text{-alkylene})-Z$ without isolation of intermediates.

The transesterification is carried out with heat in an organic solvent, for example toluene, xylene, heptane, or in a melt, strong bases such as sodium methylate, sodium ethylate, sodium hydride, metallic sodium, being used as catalyst. Reduced pressure is used to remove the released

lower alcohol from the equilibrium, the alcohol is optionally distilled off azeotropically. The transesterification takes place at temperatures which in general do not exceed 95°C . Transesterification often proceeds more favourably in a melt. If required, the free bases may be obtained in a manner known per se from acid addition salts of the tertiary amines using suitable basic compounds. Quaternisation is carried out in suitable solvents, for example acetonitrile or acetonitrile/methylene chloride, preferably at room temperature; a corresponding alkyl halide, for example alkyl bromide, is preferably used in the process as quaternising agent. Transesterification products wherein Q' represents NH are used as starting materials for those compounds in which R and R' together represent a $C_4\text{-}C_6$ -alkylene group.

Conversion into the tertiary and then quaternary compound then takes place with the aid of suitable 1,4-dihaloalkanes, 1,5-dihaloalkanes or 1,6-dihaloalkanes without isolation of intermediates.

The starting materials may be obtained analogously to known compounds—in as much as they have not already been described.

EXAMPLES

methyl di-(2-thienyl)glycolate from dimethyl oxalate and 2-thienyl magnesium bromide;

ethyl di-(2-thienyl)glycolate from (2-thienyl)glyoxylic acid and 2-thienyl lithium;

ethyl hydroxy-phenyl-(2-thienyl)acetate from methyl phenylglyoxylate and 2-thienyl magnesium bromide or from methyl (2-thienyl)glyoxylate and phenyl magnesium bromide.

Methyl 2-thienylglyoxylate and cyclohexyl or cyclopentyl magnesium bromide may be reacted in a similar manner.

Several processes are also available for the preparation of the amino alcohols.

Pseudoscopine may be obtained in accordance with M. Polonovski et al., Bull. soc. chim. 43, 79 (1928). Pseudotropenol may be removed from the mixture, (fractional crystallisation or distillation) which is obtained, for example in accordance with V. Hayakawa et al., J. Amer. Chem. Soc. 1978, 100(6), 1786 or R. Noyori et al., J. Amer. Chem. Soc. 1974, 96(10), 3336.

The corresponding methyl esters may be prepared in a conventional manner starting from 2-furylglyoxyl nitrile or 3-furylglyoxyl nitrile via the 2-furylglyoxyl acid or 3-furylglyoxyl acid which can be obtained therefrom. The corresponding glycolates are obtained from these as described using the organometallic derivatives of 2-bromothiophene or 3-bromothiophene. The organometallic compounds which can be obtained from 2-, 3- or 4-halopyridine can be reacted with methyl 2-thienylglyoxylate or methyl 3-thienylglyoxylate to give the corresponding glycolates.

Thienylglycolates, in which the thiophene ring contains fluorine in the 2- or 3-position, are prepared, for example starting from 2-fluorothiophene or 3-fluorothiophene (bromination to give 2-bromo-3-fluorothiophene or 2-bromo-5-fluorothiophene), and after conversion to the corresponding organometallic compounds, reaction with suitable glyoxylates to give the glycolates.

2-Fluorothiophene and 3-fluorothiophene can be reacted analogously to give the corresponding glyoxylates Unterhalt, Arch. Pharm. 322, 839 (1989) which in turn, as already described, may be reacted with, for example 2-thienyl or 3-thienyl derivatives, to give glycolates. Symmetrically substituted di-thienylglycolates can be prepared analogously by selecting suitable components.

A further route is available via a process analogous to the benzoin condensation and benzilic acid rearrangement.

The following examples illustrate the invention without limiting it.

EXAMPLE 1

EXAMPLE 1

Scopine di-(2-thienyl)glycolate

50.87 g (0.2 mole) of methyl di-(2-thienyl)glycolate and 31.04 g (0.2 mole) of scopine are dissolved in 100 ml of absolute toluene and reacted at a bath temperature of 90° C. with addition of 1.65 g (0.071 gram atom) of sodium in several portions. The resulting methanol is distilled off at a reaction mixture temperature of 78°-90° C. under a pressure of 500 mbar. After a reaction time of about 5 hours, the reaction mixture is stirred into a mixture of ice and hydrochloric acid. The acid phase is separated off, rendered alkaline using sodium carbonate and the free base is extracted using methylene chloride. After drying over sodium sulphate, the methylene chloride is distilled off under reduced pressure and the residue is recrystallised from acetonitrile; beige-coloured crystals (from acetonitrile).

m.p. 149°-50° C.

Yield: 33.79 g (44.7% of theoretical).

EXAMPLE 2

Scopine di-(2-thienyl)glycolate

12.72 g (0.05 mole) of methyl di-(2-thienyl)glycolate and 7.76 g (0.05 mole) of scopine are melted in a heating bath at 70° C. under a water jet vacuum. 2.70 g (0.05 mole) of sodium methylate are introduced into this melt and heated for 1 hour in a heating bath at 70° C. under a water jet vacuum and subsequently for a further hour in a heating bath at 90° C. The solidified melt is taken up in a mixture of 100 ml of water and 100 ml of methylene chloride while monitoring the temperature, and the methylene chloride phase is extracted several times using water. The methylene chloride phase is extracted using the corresponding amount of dilute hydrochloric acid. The scopine di-(2-thienyl)glycolate is extracted from the combined aqueous phases using methylene chloride after adding the corresponding amount of sodium carbonate and dried over sodium sulphate. The hydrochloride is prepared from the dried methylene chloride solution in a conventional manner. The crystals are filtered off under suction, washed using acetone and dried under reduced pressure at 35° C. Pale yellow crystals (from methanol), m.p. 238°-41° C. (decomposition);

Yield: 10.99 g (53.1% of theoretical).

The hydrochloride may be converted to the base in a conventional manner.

EXAMPLE 3

Scopine di-(2-thienyl)glycolate

38.15 g (0.15 mole) of methyl di-(2-thienyl)glycolate and 23.28 g (0.15 mole) of scopine are mixed, 0.34 g (0.015 gram atom) of sodium is added and the mixture is melted in a heating bath at 90° C. under a water jet vacuum. The reaction lasts 2.5 hours. 100 ml of absolute toluene are then added and the mixture is stirred at a heating bath temperature of 90° C. until a solution is produced. The reaction solution is cooled to room temperature and stirred into a mixture of ice and hydrochloric acid cooled using ice. The hydrochlo-

ride of the basic ester crystallising out is filtered off under suction and washed using a small amount of water and a large amount of diethyl ether. The filtrate phases are separated off and the aqueous phase is extracted using diethyl ether. The hydrochloride filtered off under suction is suspended in the (acid) aqueous phase and converted to the base while monitoring the temperature and adding the corresponding amount of sodium carbonate; the base is extracted using methylene chloride. The combined methylene chloride phases are dried over sodium sulphate. After distilling off the methylene chloride, crystals remain which are purified over active charcoal and recrystallised from acetonitrile. Pale yellow crystals (from acetonitrile), m.p. 148°-49° C.;

Yield: 39.71 g (70.1% of theoretical).

18	3α-(6,7-dehydro)-trapanyl methobromide	phenyl	110-71
19	3α-(N-ethyl)-nortropanyl methobromide	phenyl	249-50
20	3α-(N-isopropyl)- nortropanyl methobromide	phenyl	259-60
21	3α-tropanyl ethobromide	phenyl	248-49
22	3α-(N-ethyl)-nortropanyl ethobromide	phenyl	244-45
23	3α-(6β,7β-epoxy)-trapanyl ethobromide	phenyl	226
24	3α-tropanyl-β- fluoroethobromide	phenyl	241
25	3α-tropanyl methobromide	cyclohexyl	278
26	3α-(N-β-fluoroethyl)- nortropanyl methobromide	cyclohexyl	198
27	3α-tropanyl-β- fluoroethobromide	cyclohexyl	233-34
28	3α-tropanyl methobromide	cyclopentyl	260
29	3α-tropanyl ethobromide	cyclopentyl	235-36
30	3α-(N-ethyl)-nortropanyl methobromide	cyclopentyl	251-52
31	3α-(N-isopropyl)- nortropanyl methobromide	cyclopentyl	244-45
32	3α-tropanyl-β- fluoroethobromide	cyclopentyl	189-90
33	3α-(N-β-fluoroethyl)- nortropanyl methobromide	cyclopentyl	226-27
34	3α-(6,7-dehydro)-trapanyl metho-methanesulphonate	2-thienyl	225-6
35	3α-(6β,7β-epoxy)-trapanyl methobromide	2-thienyl	218-20

TABLE II-continued

Quaternary compounds of the formula			
No.	A	R ₁	M.p. [° C.]
36	3 α -tropanyl methobromide	2-thienyl	243-4
37	3 α -(6,7-dehydro)-tropanyl methobromide	2-thienyl	211-4
38	3 α -(6,7-dehydro)-tropanyl methobromide	3-thienyl	182-3*
39	3 α -(6 β ,7 β -epoxy)-tropanyl methobromide	3-thienyl	217-8
40	(+) enantiomer of No. 1		
41	(-) enantiomer of No. 1		
42	3 α -(6 β ,7 β -epoxy)-tropanyl methobromide	2-furyl	
43	3 α -(6,7-dehydro)-tropanyl methobromide	2-furyl	
44	3 α -tropanyl methobromide	2-furyl	
45	3 α -(6 β ,7 β -epoxy)-tropanyl methobromide	2-pyridyl	
46	3 α -(6,7-dehydro)-tropanyl methobromide	2-pyridyl	
47	3 α -tropanyl methobromide	2-pyridyl	
48	3 α -tropanyl methobromide	3-thienyl	
49	3 α -(6,7-dehydro)-tropanyl methobromide	cyclopentyl	
50	3 α -(6 β ,7 β -epoxy)-tropanyl methobromide	cyclohexyl	
51	3 α -(6,7-dehydro)-tropanyl methobromide	cyclohexyl	
52	3 α -(6 β ,7 β -epoxy)-tropanyl methobromide	cyclohexyl	

*contains crystalline methanol

Note:

All compounds in the table melt with decomposition.

TABLE III

Compounds of the formula			
No.	A	R ₁	M.p. [° C.] Hydrochloride
1	3 α -(6 β ,7 β -epoxy)-tropanyl	phenyl	246-7
2	3 α -(6,7-dehydro)-tropanyl	phenyl	261-2
3	3 α -(6 β ,7 β -epoxy)-tropanyl	3-thienyl	
4	3 α -(6,7-dehydro)-tropanyl	3-thienyl	
5	3 α -tropanyl	3-thienyl	
6	3 α -(N-methyl)-granatanyl	3-thienyl	

TABLE IV

Compounds of the formula			
No.	A	R ₂	M.p. [° C.] Hydrochloride
1	3 α -(6 β ,7 β -epoxy)-tropanyl	H	
2	3 α -(6,7-dehydro)-tropanyl	H	
3	3 α -(6 β ,7 β -epoxy)-tropanyl	methyl	
4	3 α -(6,7-dehydro)-tropanyl	methyl	210-2.5
5	3 α -(6 β ,7 β -epoxy)-tropanyl	methoxy	
6	3 α -(6,7-dehydro)-tropanyl	methoxy	

TABLE V

Compounds of the formula				
No.	A	R ₂	R _a M.p. [° C.]	
45	1	3 α -(6 β ,7 β -epoxy)-tropanyl	2-thienyl	5-methyl
	2	3 α -(6,7-dehydro)-tropanyl	2-thienyl	5-methyl
	3	3 α -tropanyl	2-thienyl	5-methyl
	4	3 α -(6 β ,7 β -epoxy)-tropanyl	2-(5-methyl)-thienyl	5-methyl
	5	3 α -(6,7-dehydro)-tropanyl	2-(5-methyl)-thienyl	5-methyl
	6	3 α -tropanyl	2-(5-methyl)-thienyl	5-methyl
	7	3 α -(6 β ,7 β -epoxy)-tropanyl	2-thienyl	5-fluoro
	8	3 α -(6,7-dehydro)-tropanyl	2-thienyl	5-fluoro
	9	3 α -tropanyl	2-thienyl	5-fluoro
	10	3 α -(6 β ,7 β -epoxy)-tropanyl	2-(5-fluoro)-thienyl	5-fluoro
	11	3 α -(6,7-dehydro)-tropanyl	2-(5-fluoro)-thienyl	5-fluoro
	12	3 α -tropanyl	2-(5-fluoro)-thienyl	5-fluoro

TABLE VI

Compounds of the formula

No.	A	R ₁	R ₂	M.p. [° C.]
1	3 α -(6 β ,7 β -epoxy)-tropanyl methobromide	2-thienyl	5-methyl	5
2	3 α -(6,7-dehydro)-tropanyl methobromide	2-thienyl	5-methyl	10
3	3 α -tropanyl methobromide	2-thienyl	5-methyl	15
4	3 α -(6 β ,7 β -epoxy)-tropanyl methobromide	2-(5-methyl)-thienyl	5-methyl	20
5	3 α -(6,7-dehydro)-tropanyl methobromide	2-(5-methyl)-thienyl	5-methyl	25
6	3 α -tropanyl methobromide	2-(5-methyl)-thienyl	5-methyl	30
7	3 α -(6 β ,7 β -epoxy)-tropanyl methobromide	2-thienyl	5-fluoro	35
8	3 α -(6,7-dehydro)-tropanyl methobromide	2-thienyl	5-fluoro	40
9	3 α -tropanyl methobromide	2-thienyl	5-fluoro	45
10	3 α -(6 β ,7 β -epoxy)-tropanyl methobromide	2-(5-fluoro)-thienyl	5-fluoro	50
11	3 α -(6,7-dehydro)-tropanyl methobromide	2-(5-fluoro)-thienyl	5-fluoro	55
12	3 α -tropanyl methobromide	2-(5-fluoro)-thienyl	5-fluoro	60

TABLE VII

Compounds of the formula

No.	A	R ₁	M.p. [° C.]
1	3 α -(6 β ,7 β -epoxy)-tropanyl methobromide	phenyl	211-2
2	3 α -(6,7-dehydro)-tropanyl methobromide	phenyl	158-60*
3	3 α -(6 β ,7 β -epoxy)-tropanyl methobromide	3-thienyl	
4	3 α -(6,7-dehydro)-tropanyl methobromide	3-thienyl	
5	3 α -tropanyl methobromide	3-thienyl	
6	3 α -(N-methyl)-granatanyl methobromide	3-thienyl	

*(with crystalline methanol)

TABLE VIII

Quaternary compounds of the formula

No.	A	R ₂	M.p. [° C.]
1	3 α -(6 β ,7 β -epoxy)-tropanyl methobromide	H	
2	3 α -(6,7-dehydro)-tropanyl methobromide	H	
3	3 α -(6 β ,7 β -epoxy)-tropanyl methobromide	methyl	
4	3 α -(6,7-dehydro)-tropanyl methobromide	methyl	206-8
5	3 α -tropanyl methobromide	methoxy	
6	3 α -(N-methyl)-tropanyl methobromide	methoxy	

We claim:

1. A compound of the formula

wherein

Q is a group of the formula $[-\text{CH}_2-\text{CH}_2-]$, $-\text{CH}=\text{CH}-$ orR and R' are each independently C₁-C₄-alkyl; R₁ is thienyl, phenyl, cyclopentyl or cyclohexyl; and X- is a physiologically acceptable anion.

15

2. A compound in accordance with claim 1, of the formula

wherein

R is CH₃, C₂H₅, n-C₃H₇, or i-C₃H₇;R' is CH₃; andR₁, Q and X⁻ are as defined in claim 1.3. A compound in accordance with claim 2 wherein R₁ is thiienyl.4. A compound in accordance with claim 2 wherein X⁻ is Br⁻ or [CH₃SO₃] CH₃SO₃⁻.

5. A compound of the formula

wherein X⁻ is a physiologically acceptable anion.

6. A compound of the formula

wherein X⁻ is a physiologically acceptable anion.

16

7. A compound of the formula

8. A compound of the formula

wherein R₁ is 2-thienyl and A is 3α-(6,7-dehydro)-tropanyl methobromide.

9. A compound of the formula

wherein R₁ is 2-thienyl and A is 3β-tropanyl methobromide.]

10. A compound of the formula

45 wherein R₁ is cyclopentyl and A is 3α-(N-isopropyl)-nortropanyl methobromide.]

11. A method for treating chronic obstructive bronchitis which comprises administering, by inhalation, to a subject suffering from the same, a therapeutic amount of a compound in accordance with claims 1, 2, 3, 4, 6, 7, or 8[9, 10].

12. A method for treating slight to moderately severe asthma which comprises administering, by inhalation, to a subject suffering from the same, a therapeutic amount of a compound in accordance with claims 1, 2, 3, 4, 6, 7, 8, 9, 10.]

13. A method for treating vagally induced sinus bradycardia which comprises administering, by the intravenous or oral routes, to a subject suffering from the same, a therapeutic amount of a compound in accordance with claims 1, 2, 3, 4, 6, 7, or 8[9, 10].

14. A pharmaceutical composition, for administration by inhalation, suitable for the treatment of chronic obstructive bronchitis [or slight to moderately severe asthma], which comprises a compound in accordance with claims 1, 2, 3, 4, 6, 7, or 8[9, 10].

15. A pharmaceutical composition for oral administration, suitable for the treatment of vagally induced sinus

17

bradycardia, which comprises a compound in accordance with claims 1, 2, 3, 4, 6, 7, or 8[. 9, 10].

16. A pharmaceutical composition, for intravenous administration, suitable for the treatment of vagally induced sinus bradycardia, which comprises a compound in accordance with claims 1, 2, 3, 4, 6, 7, or 8[. 9, 10].

17. *A method for treating chronic obstructive bronchitis which comprises administering, by inhalation, to a subject suffering from the same, a therapeutic amount of a compound in accordance with claim 5.*

18

18. *A pharmaceutical composition, for administration by inhalation, suitable for the treatment of chronic obstructive bronchitis, which comprises a compound in accordance with claim 5.*

19. *A pharmaceutical composition, for administration by inhalation, suitable for the treatment of chronic obstructive bronchitis, comprising an inhalation powder comprising a compound in accordance with claim 5.*

* * * * *

UNITED STATES PATENT AND TRADEMARK OFFICE
CERTIFICATE OF CORRECTION

PATENT NO. : RE 39,820 E
APPLICATION NO. : 11/254213
DATED : September 4, 2007
INVENTOR(S) : Banholzer et al.

Page 1 of 1

It is certified that error appears in the above-identified patent and that said Letters Patent is hereby corrected as shown below:

Column 15, line 29, change “[CH₃SO₃]CH₃SO₃-” to --[CH₃SO₃] CH₃SO₃^---

Column 15, line 67, change “onion.” to --anion.--

Column 16, line 10, after the figure, insert --wherein R₁ is 2-thienyl and A is 3 α -(6 β , 7 β -epoxy)-tropanyl methobromide.--

Column 16, line 50, change “1, 2, 3, 4, 6, 7, or 8 [9, 10]” to --1, 2, 3, 4, 6, 7, or 8 [, 9 or 10]--

Column 16, line 54, change “1, 2, 3, 4, 6, 7, 8, 9, 10” to --1, 2, 3, 4, 6, 7, 8, 9 or 10--

Column 16, line 59, change “1, 2, 3, 4, 6, 7, or 8[9, 10]” to --1, 2, 3, 4, 6, 7, or 8 [, 9 or 10]--

Column 16, line 64, change “1, 2, 3, 4, 6, 7, or 8[9, 10]” to --1, 2, 3, 4, 6, 7, or 8 [, 9 or 10]--

Column 17, line 2, change “1, 2, 3, 4, 6, 7, or 8[9, 10]” to --1, 2, 3, 4, 6, 7, or 8 [, 9 or 10]--

Column 17, line 6, change “1, 2, 3, 4, 6, 7, or 8[9, 10]” to --1, 2, 3, 4, 6, 7, or 8 [, 9 or 10]--

Signed and Sealed this

Eighth Day of January, 2008

JON W. DUDAS
Director of the United States Patent and Trademark Office
